UNITED STATES PATENT OFFICE.

MOSES C. JOHNSON, OF HARTFORD, CONNECTICUT.

SPEED-CONTROLLING AND REVERSING MECHANISM.

SPECIFICATION forming part of Letters Patent No. 699,873, dated May 13, 1902.

Application filed January 18, 1902. Serial No. 90,261. (No model.)

To all whom it may concern:

Be it known that I, MOSES C. JOHNSON, a citizen of the United States, residing at Hartford, in the county of Hartford and State of Connecticut, have invented certain new and useful Improvements in Speed-Controlling and Reversing Mechanism, of which the following is a specification.

My invention relates to speed-controlling and reversing mechanism; and it has for its object the provision of improved mechanism of this character which will be of simple construction, reliable in operation, and will permit the desired speed to be given to the driven shaft when rotated in either direction.

Primarily my invention is designed for use with motor conveyances (either land or water) of any desired kind. In these conveyances—for instance, an automobile or a launch—it is frequently desirable to drive the vehicle forward at full speed and then again at a reduced speed and also quickly to reverse the direction of its motion. My invention is intended to carry out these results in a simple way by an arrangement of mechanism under the control of the chauffeur or engineer, and this mechanism is so constructed and arranged that said results may be accomplished practically without noise and with a minimum of frictional resistance and so that the desired changes in speed or of the direction of motion may be quickly effected.

A further object of the invention is the provision of mechanism for rotating the driven shaft in first one direction and then in the other direction, said mechanism being under the control of a cam of peculiar construction, as will be hereinafter described.

A further object of the invention is the provision of gearing so arranged and combined with the driven shaft that when said shaft is rotated at full speed forward all of said gearing will remain idle, thereby avoiding noise and an unnecessary expenditure of power in driving the same.

Other objects of the invention will be set forth in the detailed description hereinafter given.

In the accompanying drawings, Figure 1 is a side elevation of the preferred form of my invention with the casing in section. Fig. 2

is a horizontal section on line 2 2 of Fig. 1 looking downward. Fig. 3 is a right-hand end elevation. Fig. 4 is a horizontal section on line 4 4 of Fig. 3. Fig. 5 is a vertical section on line 5 5 of Fig. 2 looking in the direction of the arrow. Figs. 6, 7, 8, 9, and 10 are diagrammatic views of a form of cam which may be employed. Fig. 11 is a side view, with the casing partially broken away, of a modification of the invention. Fig. 12 is a horizontal section on line 12 12 of Fig. 11. Fig. 13 is an end elevation of the modified construction. Fig. 14 is a horizontal section thereof on line 14 14 of Fig. 13; and Fig. 15 is a detail view, hereinafter described.

Like characters designate similar parts throughout the several views.

Referring to the drawings, the numeral 1 designates the frame of my improved machine, and this frame, while shown in the form of a casing for the reception of a lubricant for the parts to work in, may be of any desired construction.

Designated by the numeral 2 is a sprocket-wheel or it may be other gear having a hub 2', said gear being driven by any suitable means connected with the motor, which may be of any desired type. This hub 2' is splined or otherwise connected to a sleeve or quill 3, thereby continuously rotating said sleeve when power is applied to the gear 2. Mounted within the sleeve or quill 3 is a driven shaft 4, which may be of any required length and in the exemplification given has splined to its end a device 5, having a hub 5', said device being shown as a sprocket-wheel, although it may be a gear, pulley, or other element, for transmitting motion from the driven shaft to the device or devices for propelling the conveyance. In some instances the sprocket-wheel or power-transmitting element 5 may be omitted and the shaft 4 connected directly to a propeller or other instrumentality it is desired to actuate, the invention not being limited to the sprocket-wheel illustrated nor to any particular device secured to said shaft. On one side the frame or casing 1 is provided with a tubular projection 6' for receiving a bushing 6, flanged on its inner side at 6'', said bushing serving as a journal-box for the sleeve or quill 3, and on

its other side with a hollow projection 7, in which is fitted a bushing 8, acting as a journal-box for the driven shaft 4.

Splined or otherwise connected to the sleeve 5 or quill 3 is the hub 9' of a friction-cup 9, and, as will be obvious, when said cup is connected to the shaft 4 the latter will be driven at full speed in a forward direction, either by a motor connected directly with the 10 quill 3 or indirectly to said quill by a sprocket-chain (not shown) and the sprocket-wheel 2, as may be desired.

Loosely surrounding the hub 9' of friction-cup 9 is a sleeve 10, having a small gear 11 15 at one end and a large gear 12 at its opposite extremity. Formed in the inner face of the gear 12 is a concentric groove 12', and fitted in sockets of said gear are clutch-pins 13, having heads 13', the latter being in the 20 groove 12', as illustrated in Fig. 2. Projecting from the web of the friction-cup 9 are clutch-pins 14, which when the sleeve 10 is shifted on the hub 9', by means hereinafter described, will engage with said clutch-pins 13.

25 Within the friction-cup 9 is an expansion-ring 15, secured to a hub or carrier 16, and while this ring may be actuated in any desired way or another suitable clutch device may be substituted therefor, if desired, I have 30 shown in Fig. 15 as a means for accomplishing this result a pair of levers 17, pivoted to the expansion-ring. For actuating these levers, and thereby locking the expansion-ring to the friction-cup 9, a wedge-block 18 is secured to a shifting-ring 19, said ring being capable of reciprocatory movement upon the hub or carrier 16, as will hereinafter be described. This hub or carrier is provided with longitudinal open slots 20 for the reception 40 of sliding clutch-pins 21, and these pins are actuated at the proper time by studs 22, projecting from the inner side of the shifting ring 19, the shanks of said studs passing through the slots and entering the pins, 45 as illustrated by dotted lines in Fig. 2. Fitted in a groove of the shifting ring 19 are shoes 23, and said shoes are connected by bolts 24 to the arms 25' of a yoke or forked lever 25, said lever having a hub 26, which is 50 mounted for rocking movement upon a rod 27, extending transversely of the casing or frame 1, as illustrated in Fig. 5, said rod passing through a hollow boss 27' of the frame and through a projection 34', rising 55 from the bearing 34 and being secured in position by a pin 27', as shown in Fig. 4. Projecting from the hub of this forked lever is an arm 28, articulated at 29 to the link 30, and at about its middle portion this link is 60 provided with a stud 31, which carries an anti-friction-roller 31', (see Figs. 1 and 4,) working in the groove 32' of a cam 32 of peculiar construction, said cam having a hub 32', secured to a rock-shaft 33, journaled in bearings 34 34' of the frame. At its end opposite arm 28 the link 30 is articulated to a pin 35' 65 on an arm 35, an angular extension 36 of

which is mounted for rocking movement in a hollow boss 36' of the frame and is prevented from endwise movement therein by a pin 36'. 70

Sleeve 10 is provided with flanges 10', and in the groove between said flanges are shoes 37, carrying pins 38, over which are fitted eyes in the ends of a yoke or fork 39, having a hub 39', journaled on a rod 40, passing 75 through a hollow boss 41 of the frame and a projection 42 of the bearing 34', said rod being secured in place by a pin 43, as shown in Fig. 4. Projecting from hub 39' is an arm 44, bifurcated at its free end at 44' to fit over 80 the pin 35' of arm 35. By pivoting the link 30 to the arm 28 at one end and to the swinging arm 35 at its opposite end the pin 31, carried by said link, is always kept central in the cam-groove, thus avoiding any binding action of said pin or the roller 31', carried thereby, against the walls of said groove. 85

Fixedly secured in the frame or casing 1 is a rod or shaft 45, and loosely mounted thereon is a sleeve 46, having a fixed gear 47 at one 90 end, a loose gear 48 at its opposite end, and a loose gear 49 intermediate the gears 47 and 48.

Loosely mounted on the driven shaft 4, adjacent to the carrier 16, is a gear 50, the web 95 of which is provided with clutch-pins 51 for a purpose hereinafter set forth, and said gear is in mesh with the gear 47, fixed to sleeve 46. (See Figs. 2 and 5.) Shown by full lines in Fig. 2 and by dotted lines in Fig. 5 is an 100 idler-pinion 52, which is in mesh with the gear 11 of sleeve 10 and with the gear 48, loosely mounted on sleeve 46.

Each of the gears 48 and 49 is formed as a shell or friction-cup for the reception of expansion-rings 53 and 54, respectively, and these rings carry pivoted levers 55 55', respectively, of the kind shown in Fig. 15 and clearly disclosed in my patent dated August 25, 1891, No. 458,423. 110

Secured to the sleeve 46 by a spline 55' is a sleeve 56, to which the expansion-rings 53 and 54 are attached and upon which is mounted a shipper-ring 57, carrying on its under side wedge-blocks 58 59, respectively, for actuating, when said ring is shifted, the pivoted levers 55 or 55', and thus causing said levers to expand the rings and lock either the gear 48 or the gear 49 to the sleeve 46. The shipper-ring 57 is grooved to receive shoes 60, 115 and over pins 61, projecting from said shoes, are fitted the eyes of a fork 62, said fork having a hub 62', mounted on a rod 40'. Projecting from said hub is an arm 63, having a slot 63' for the reception of the end of a link 120 64, secured in said slot by a pivot pin or bolt 65, said link carrying intermediate its length a pin 66, upon which may be fitted an anti-friction-roller 67, working in the groove of the cam 32, as shown in Fig. 4. At its end 125 opposite the yoke 62 link 64 is pivoted to a rocking arm 68, the stem 68' of which is journaled in a hollow stud 69, projecting from the inner side of the frame, and is secured 130

therein by a pin 68², as shown in Fig. 5, in virtue of which construction the link will swing without affecting the position of the roller in the cam-groove, as heretofore described with reference to the link 30 and pin 31.

Secured to one end of the cam-shaft 33 is a toothed segment 70, and for actuating this segment any desired means, either manually or automatically operated, may be employed; but I have shown for the purpose a curved rack or sector 71, the body of which projects from a hub 71', sleeved upon a stud 72 of frame 1, said hub having integral therewith or attached thereto a hand-lever 73, as shown in Figs. 3 and 4.

In the operation of the preferred form of my invention should it be desired to drive the conveyance full speed forward the lever 73 is shifted to the position represented in Fig. 3, and this action causes the rack or sector to turn the segment 70 and shaft 33 toward the right and the cam 32 to act upon pin 31 and shift the link 30, arm 28, fork 25, and shiftable ring 19, carrying wedge-block 18, the latter actuating the pivoted levers 17 and causing them to expand the split ring 15 and lock the body 16 (splined to shaft 4) to the friction-cup 9, the sleeve 9' of such cup being splined to the quill 3, as before stated. As the link 30 is moved to the right in the manner above set forth the fork 39 is shifted by the connections described to the left, thereby sliding the sleeve 10, carrying gears 11 and 12, along the hub 9' and disconnecting the clutch-pins 13, carried by gear 12, from the clutch-pins 14 of the friction-cup 9, as shown in Fig. 2. Now by applying power in any desired manner to the quill 3 said quill, the sleeve 9', splined thereto, the friction-cup 9, clutched to the carrier or body 16, and the driven shaft 4, to which said carrier is splined, will be driven at full speed in a forward direction. When the cam 32 is shifted to accomplish the results just described, it is moved from the position shown in Fig. 6 in the direction of the arrow F in the diagrams Figs. 7, 8, and 9 and the active portion a of its groove has caused the pin 31 to move to the right from the position illustrated by dotted line b to the position illustrated by the full lines of said pin in Fig. 9, it being understood, of course, that Fig. 6 represents the neutral or non-active position of said cam with all the parts of the mechanism at rest. When this has been accomplished, it will thus be seen that all of the mechanism within the casing or frame is idle with the exception of the shaft 4, the quill 3, and the parts connecting said shaft and quill, as above described, thereby avoiding noise and friction and the jar incident to the rotation of gearing while the conveyance or other instrumentality is being propelled in the usual way. Should it be desired to change the speed of the conveyance in a forward direction, the lever 73 is first shifted to turn the cam 32 about forty-five degrees to the stop

position, (represented by the diagram Fig. 8,) and during this motion of the cam the active portion a thereof will actuate the link 30 and through the connections described will shift the sleeve 10 along the hub 9' and the shift-ring 19 along the carrier 16, thereby throwing the clutch-pins 13 and 21 into position to engage with the complementary clutch-pins 14 of friction-cup 9 and the pins 51 of the gear-wheel 50. This action places the parts in position for actuating the shaft 4 in a slow forward direction, and after it has been accomplished the cam 32 is shifted another forty-five degrees to the left, or to the position represented by the diagram Fig. 7, and as it turns to said position its active portion c will actuate the pin 66 of the link 64 to the position represented by full lines in said Fig. 7, and this link will through the connections described reciprocate the shift-ring 57 toward the right in Figs. 1 and 2 and will cause the wedge-block 59 of said ring to operate the pivoted levers 55', which will expand the expansion-ring 54 and lock the gear 49 to the sleeve 46, thereby causing said sleeve to be turned and its pinion 47 to rotate the gear 50, now connected to the shaft 4 by the pins 21 and 51, (the carrier 16, in which pins 21 are mounted, being splined to the shaft,) and thereby rotate said shaft slowly in a forward direction. Should it be desired to reverse the motion of the conveyance, the cam 32 is again shifted forty-five degrees, causing the active portion d of its surface to bring the pins 31 and 66 to the stop position illustrated in Fig. 6, where all the mechanism is at rest, and is then shifted another forty-five degrees to cause its active portion e to shift the pin 66, link 64, connected to said pin, and yoke 62, thereby throwing the shift-ring 57 to the left in Fig. 2 and causing the wedge-block 58 to actuate the levers 55, operate the expansion-ring 53, and lock the sleeve 56, splined to the hollow shaft 46, to the gear 48, and inasmuch as said gear 48 is in mesh with the idler 52 and as the latter is in engagement with the pinion 11 of sleeve 10, now clutched to the friction-cup 9 in the manner above stated, (the hub of said cup being splined to the quill 3,) it will be seen that as said quill is rotated it will through said parts actuate the sleeve 10 and through the gears 11, 52, 48, and 47 impart a reverse motion to the gear 50, now clutched to the carrier 16, splined to the shaft, and will thereby rotate said shaft in a reverse direction. The gear 49 in mesh with gear 12 of sleeve 10 rotates idly on the sleeve 46, as will be obvious, when this reverse connection is made.

It will be understood from the above description that my improved cam, which has a circumference of three hundred and sixty degrees, has a plain or non-active groove for one hundred and eighty degrees of said circumference and that the remaining one hundred and eighty degrees of the circumference

of the cam is divided into four active parts of forty-five degrees each, the construction being such that before any change in the mode of operation of the mechanism is established 5 said mechanism will be first brought to a stop position. This is important for many reasons, for, as will be obvious, if the chauffeur or engineer should through excitement or fear become obfuscated and not be aware of what 10 he is doing any movement by him of the lever 73 to shift the cam will first bring the mechanism to a full stop, and thus will avoid all danger of accident.

In practice the lever 73 will be combined 15 with the usual quadrant or other device upon which the symbols for indicating the motion of the lever will be placed, and common adjuncts will be employed with said lever for securing it temporarily in position when the 20 cam is actuated step by step in the manner above described. The cam may either be left-hand, as shown, or right-hand, as desired, for one construction will work as well as the other.

In the modification represented by Figs. 11 25 to 14, inclusive, some of the parts illustrated in the views of the preferred form of the invention are changed and others are omitted, and no provision is made for stopping the motion of the gearing on the counter-shaft or 30 sleeve while the driven shaft is actuated at either slow or full speed in its forward direction. In the views of this modification the elemental parts, like those shown in the mechanism of the preferred form, are designated 35 by the same numerals; but where there has been a change in any part it is described and indicated on the drawings by a different character.

In the figures just described the frame or 40 casing 1, sprocket-wheel 2 2', quill 3, driven shaft 4, sprocket-wheel 5 5', bearings 6, 6², and 8, tubular bosses 6' and 7, friction-cup 9, having hub 9', splined to quill 3, expansion-ring 15, carrier or body 16, splined to driven shaft 4 and to which said expansion-ring is secured, 45 levers 17, pivoted to the expansion-ring, wedge-block 18, shifting ring 19, shoes 23, yoke 25, rod 27, arm 28, link 30, carrying pin 31, cam 32, shaft 33, bearings 34 34', rocker 50 35, sleeved upon rod 36, tubular sleeve or shaft 46, carrying gear 47, gears 48 and 49, loosely mounted on said shaft 46, expansion rings 53 54, sleeve 56, splined to tubular shaft 46, wedge-blocks 58 59, pivoted levers 55 55', stationary shaft or rod 45, shifting ring 57, link 64, carrying pin 66, upon which is mounted antifriction-roller 67, rod 40', yoke 62, rocker 68 68', lever 73, sector 71, stud 72, and gear 70 are like those indicated in Figs. 1 to 10, 55 inclusive, of the drawings and are designated by the same numerals. In the modification the sliding sleeve 10, with its gears 11 and 12, the clutch-pins 13 and 14, and the clutch-pins 21 and 51 are omitted, and in place of 60 the loose gear 50 on driven shaft 4 a gear 74, keyed or otherwise secured to said shaft at 75, is employed, and the friction-cup 9

is provided with a peripheral gear 76, in mesh with the gear 49 of sleeve 46 and also carries at its end opposite to said gear 76 a small 70 gear 11, in mesh with an idler 52, which in turn intermeshes with a larger gear 48, loosely mounted upon said tubular shaft 46. To the shaft 33 is secured the cam 32, having groove 32², one half or one hundred and 75 eighty degrees of which is formed with plain walls, as shown in Fig. 11, and the other half of which is divided into right-and-left inclined portions *a c d e*, as illustrated in Fig. 7. Fitted in the cam-groove 32² are the anti-friction-rollers 31' 67, mounted, respectively, 80 upon the pins 31 and 66 of the links 30 and 64, as illustrated in Fig. 14, and these links are connected to the arms 28 and 63 of the yokes 25 and 62 and operate in the same 85 manner as they do in the preferred form of the invention. In the position of the parts represented in the various figures of the modification the mechanism is shown as arranged to impart a slow-speed forward movement to 90 the driven shaft 4, and the shifting ring 57 has been moved to actuate the levers 55', and thereby clutch the gear 49 to the sleeve 56, said sleeve being splined to the shaft 46 at 80, as illustrated in Fig. 12, and the lever 73 95 has been turned to cause its sector 71 to rock the segment 70 and cam-shaft 33 to the position represented in Fig. 13. Inasmuch as power is applied to the quill 3 by sprocket-wheel 2 or in any other desired manner and 100 as said quill is splined to the hub 9' of friction-cup 9, and it therefore continuously rotates with said quill, it will be seen that the gear 76 on said friction-cup will rotate gear 49, now locked to the tubular shaft 46, thereby causing said shaft to turn and its gear 47, in mesh with the larger gear 74, keyed to the shaft 4, to rotate said shaft slowly in a forward direction. Should it be desired to rotate shaft 4 at a fast speed forward, the lever 110 73 is shifted to its extreme position toward the right in Fig. 13, thereby causing the inclined portion *a* of the cam 32 to act upon the antifriction-roller 31' of pin 31 and to shift the link 30 to the right, and said link 115 being articulated to the arm 28 of yoke 25 will actuate the shifting ring 19 toward the left and force the wedge-block 18, carried by said ring, into contact with the pivoted levers 17, thereby expanding the expansion-ring 15 120 and locking the carrier or body 16 to the friction-cup 9. In this fast forward position of the gearing the quill 3, being continuously rotated, as stated, and being splined to the hub 9' of friction-cup 9, will rotate the carrier 16, and consequently through said carrier the shaft 4, directly in a fast forward direction, and preceding the clutching of the friction-cup 9 to the carrier or body 16 the inclined portion *c* of the cam 32 will act upon 125 the roller 67 of pin 66 and will shift link 64 and ring 57 to a neutral position between the two gears 48 and 49, as shown in Fig. 9. Should it be desired to reverse the movement 130

of the driven shaft 4, the lever 73 is shifted to its extreme position toward the left, thereby causing the part *e* of cam 32 to actuate the yoke 62 and force the shifting ring 57, carrying wedge-block 58, in the same direction, thus operating the pivoted levers 55 and expansion-ring 53 and locking the gear 48 to the shaft 46. Just before this action occurs another portion of the cam, of course, acts upon the link 30 and forces the shifting ring 19 toward the right, thereby releasing through the pivoted levers described the expansion-ring 15. When the mechanism is in this reverse position, the continuously-rotated quill 3, splined to hub 9', will rotate said hub and the gear 11 attached thereto and through idler 52 will impart rotary movement to the gear 48, now locked to the tubular shaft 46, and through said shaft and its gear 47 to the gear 74, keyed to the shaft 4, thereby rotating said shaft 4 in a reverse direction, as stated. When the connections above described are made, it will be seen that when the shaft is driven slowly in a forward direction the gear 49 is clutched to tubular shaft 46 and that the gear 48 rotates loosely on said shaft, that when said shaft 4 is driven at fast speed forward the gears 48 and 49 and the tubular shaft 46 and its gear 47 rotate idly 25 without imparting movement to any of the parts, and that when the mechanism is set for a reverse motion of the driven shaft 4 the gear 49 rotates idly on said shaft 46. In this construction, as in the preferred form illustrated and above described, the cam 32 is of such form that upon any movement of the lever 73 to actuate the same and turn the shaft 33 and said cams the mechanism will be brought first to a full stop. Then the 30 parts it is desired to employ for rotating the shaft at one speed will be thrown into action. Then the mechanism will again be brought to a stop. Then the parts for rotating the shaft at another speed will be thrown into 35 action. Then another stop will be made; and, finally, the parts for reversing will be thrown into action. Therefore it will be seen that should the chauffeur or engineer become bewildered through excitement or otherwise, 40 no matter how the lever 73 is thrown, provision is made for the full stop of the mechanism, thereby avoiding all liability of danger to passengers and of accident to the conveyance. In this form of my invention while 45 it is fully operative to produce the desired results I regard the continuously-rotating gears as somewhat objectionable on account of the noise and frictional wear and tear attendant thereupon, and consequently in the 50 preferred form of the invention provision is made for keeping said gears idle when the shaft 4 is being driven full speed ahead.

My invention is not limited to the precise construction illustrated and described nor to any specific kind or proportionate arrangement of gearing. Neither is it limited to the arrangement of the various parts illustrated

in the two forms thereof nor to any specific means for applying power to the mechanism, for, as will be obvious, many mechanical changes may be made without departure from the scope thereof. So, too, the cam mechanism and the parts connected therewith may be variously modified and any forms of clutches suitable for the purpose may be employed as substitutes for those shown without departure from the invention.

In my application filed in the United States Patent Office December 11, 1901, Serial No. 85,577, certain features of the present invention are set forth, and no claim is herein made to the subject-matter covered by said application.

Having thus described my invention, what I claim is—

1. The combination, with a shaft, of a quill loose on the shaft; means for rotating the quill; a clutch element sleeved upon and connected to the quill; gearing carried by said clutch element; a complementary clutch element; a carrier for said complementary clutch element, said carrier being rigid with the shaft; a gear on the shaft adjacent to said carrier; means for actuating the complementary clutch element to lock said clutch element sleeved upon the quill to the carrier, and means for connecting the gearing of the clutch element sleeved upon the quill with the gear upon the shaft.

2. The combination, with a shaft, of a quill loose on said shaft; means for rotating said quill; a clutch element sleeved upon and connected to the quill; a carrier rigid with the shaft; a complementary clutch element mounted on the carrier; means for actuating said complementary clutch element; and shaft-reversing mechanism controlled by the quill.

3. The combination, with a shaft, of a quill loosely mounted on said shaft; a device secured to said quill; a gear carried by said device; a carrier secured to the shaft; mechanism for clutching said device to the carrier; means for actuating said clutching mechanism; a counter-shaft; a gear loosely mounted on said counter-shaft; means for connecting said gear to the counter-shaft; a gear fixedly mounted on the counter-shaft; and mechanism connecting said gear with the shaft.

4. The combination, with a driven shaft, of a quill loosely mounted on said shaft; a device having a hub secured to said quill; a counter-shaft; gearing loosely mounted on said counter-shaft; a gear fixed to the counter-shaft; a gear carried by the driven shaft and in mesh with said fixed gear; gearing in mesh with the loose gears of the counter-shaft, said gearing being carried by the device having a hub secured to the quill; an idler for connecting one of the gears carried by the hub with one of the gears of the counter-shaft; and means for connecting the gear in mesh with the idler with said counter-shaft.

5. The combination, with a driven shaft, of a quill loosely mounted on said shaft; means

- for rotating the quill; a device having gears carried by the quill; a counter-shaft; gears loosely mounted on said counter-shaft; a gear fixed to said counter-shaft; an idler between 5 one of the gears of the device on the quill and one of the loosely-mounted gears on the counter-shaft; a gear carried by the driven shaft and in mesh with the fixed gear of the counter-shaft; means for connecting said gear to the driven shaft; devices for alternately clutching the loosely-mounted gears to the counter-shaft; a cam; connections from said cam for actuating said devices; and means for actuating the cam.
- 15 6. The combination, with a driven shaft, of a quill mounted on said shaft; a sleeve secured to the quill; gearing carried by the sleeve; a counter-shaft; a gear loosely mounted on said counter-shaft and in engagement 20 with an element of the gearing carried by the sleeve; another gear loosely mounted on said counter-shaft; an idler connecting said gear with another member of the gearing carried by the sleeve; means for alternately clutching the loosely-mounted gears to the counter-shaft; a cam-shaft; a cam carried by said cam-shaft; lever-and-link connections between said cam and the clutch-actuating devices of the counter-shaft; a fixed gear carried by the counter-shaft; a gear in engagement with said fixed gear; means for securing said gear to the driven shaft; and means for actuating the cam-shaft.
- 25 7. The combination, with a shiftable element, of means for actuating said element; a link connected to said actuating means; a rocker movably connected to and supporting said link; a cam; a device carried by the link and actuated by said cam; and means for actuating said cam.
- 30 8. The combination, with a shiftable element, of a yoke for actuating said element; an arm projecting from said yoke; a link articulated to the arm; a rocker pivoted to the link; a cam; a device carried by the link and bearing against the cam; and means for actuating said cam.
- 35 9. The combination, with a driven shaft, of mechanism for actuating said shaft at one speed in a forward direction; mechanism for actuating said shaft at a different speed in a forward direction; mechanism for reversing the rotation of said shaft; a cam; links carrying devices acted upon by said cam; means for connecting one of said links with the reversing mechanism; means for connecting the other link with the mechanisms for driving the shaft in a forward direction; and rockers to which said links are pivoted.
- 40 10. The combination, with a driven shaft, of a counter-shaft; gearing connecting said driven shaft and counter-shaft; means for locking an element of said gearing to the counter-shaft when it is desired to rotate the 45 driven shaft at a slow speed in a forward direction; means for connecting another element of said gearing to the counter-shaft when it is desired to reverse the rotation of said driven shaft; means for rotating the driven shaft at a fast speed in a forward direction; a cam; and mechanism for connecting said cam with the means for imparting rotary movement to said shaft.
- 50 11. The combination, with a driven shaft, of a carrier secured to said driven shaft; a friction-cup; a continuously-driven quill to which said cup is connected; an expansion-ring between the friction-cup and carrier; a counter-shaft; gearing between said friction-cup and the counter-shaft; a fixed gear carried by the counter-shaft; a gear carried by the driven shaft and in engagement with said fixed gear of the counter-shaft; means for connecting the gear carried by the driven shaft to said driven shaft; means for alternately clutching certain gears of the counter-shaft to said shaft; means for actuating the expansion-ring in the friction-cup; a cam; and connections from the cam for actuating all of said means.
- 55 12. The combination, with a driven shaft, of a quill loose on said shaft; means for rotating the quill; a sleeve secured to said quill; a counter-shaft; a pair of gears loosely mounted on said counter-shaft; a pair of gears carried by the sleeve on the quill, one of which is in engagement with one of the loosely-mounted gears of the counter-shaft; an idler in engagement with the other loosely-mounted gear of the counter-shaft and with the other gear of the pair carried by the quill; gearing for connecting the counter and driven shafts; devices for clutching the loosely-mounted gears to said counter-shaft; and a cam for actuating said devices.
- 60 13. The combination, with a driven shaft, of a quill loose on said shaft; means for rotating the quill; a hub or carrier secured to the driven shaft; means for connecting said quill to the hub or carrier; a counter-shaft; a gear fixed to said counter-shaft; a gear on the driven shaft; means for connecting said gear to the driven shaft; gears loosely mounted on the counter-shaft; means for clutching either of said gears to the counter-shaft; a cam and connections for actuating said means; gears carried by the quill; and a gear for connecting one of said gears carried by the quill with one of the gears of the counter-shaft.
- 65 14. The combination, with a driven shaft, of a quill loose on said driven shaft; means for rotating said quill; a hub or carrier secured to the driven shaft; means for connecting the quill to said hub or carrier to rotate said driven shaft at a fast speed in a forward direction; means for connecting the quill with the driven shaft to rotate the driven shaft at a different speed in a forward direction; and means controlled by the quill for reversing the movement of the driven shaft.
- 70 15. The combination, with a driven shaft, of a quill loose on said shaft; means for rotating the quill; a pair of gears controlled by the quill; means for connecting the quill to

the driven shaft to turn said shaft at a fast speed in a forward direction; a counter-shaft; a pair of gears loosely mounted on said counter-shaft, one of said gears being in mesh with 5 one of the gears controlled by the quill; a gear connecting the other loose gear of the counter-shaft with the other gear controlled by the quill; clutch connections for clutching said loosely-mounted gears to the counter-shaft; means for actuating said connections; 10 a gear fixed to the counter-shaft; and means connecting said gear with the driven shaft.

16. The combination, with a driven shaft, of a quill; means for rotating said quill; a 15 sleeve rotating with the quill; means for connecting said sleeve to the driven shaft to drive the same at a certain speed; means for connecting said quill with the driven shaft to rotate the same at a different speed; means for 20 connecting said quill with the driven shaft to reverse the motion thereof; a cam; and devices actuated by said cam for effecting the connections set forth.

17. The combination, with a driven shaft, 25 of a quill loosely mounted on said shaft; a hub or sleeve secured to the quill; a sleeve mounted for reciprocatory movement on said hub or sleeve; clutch devices for connecting the sleeve with the hub; gearing carried by 30 the reciprocatory sleeve; a counter-shaft; a gear loosely mounted upon the counter-shaft and in engagement with an element of the gearing of the sleeve; a gear fixed to the counter-shaft; a gear in engagement with 35 said fixed gear and carried by the driven shaft; and means for connecting said last-named gear to said driven shaft.

18. The combination, with a driven shaft, 40 of a quill loosely mounted on said shaft; a hub secured to the quill; a reciprocatory sleeve carried by the hub; means for reciprocating said sleeve; clutch devices connecting said sleeve and hub; a counter-shaft; gearing for connecting the sleeve with said counter-shaft; a fixed gear carried by the counter-shaft; a gear in engagement with said fixed gear, and carried by the driven shaft; and means for connecting said gear to the driven 45 shaft.

50 19. The combination, with a shaft, of a quill loosely mounted on said shaft; means for rotating said quill; a hub splined to the quill; a reciprocatory sleeve mounted upon the hub; means for clutching said reciprocatory sleeve to the hub; a gear carried by the sleeve; a counter-shaft; a gear loosely mounted on said counter-shaft; means for clutching said gear to the counter-shaft; a fixed gear carried by the counter-shaft; a gear 55 loosely mounted on the driven shaft; and means for clutching said gear to the driven shaft.

60 20. The combination, with a driven shaft, of a quill loose on said shaft; means for rotating the quill; a hub splined to said quill; a friction-cup carried by the hub; an expansion-ring located within said friction-cup; a

carrier secured to the driven shaft; means for locking the expansion-ring to the friction-cup; a sleeve mounted on the hub of the friction-cup; means for reciprocating said sleeve; clutch devices carried by the sleeve; clutch devices carried by the friction-cup; gearing carried by the sleeve; a counter-shaft; gearing carried by said counter-shaft; means for locking said gearing to the counter-shaft; and 70 gearing connecting the counter-shaft with the driven shaft.

21. The combination, with a shaft, of a quill loosely mounted on said shaft; means for 80 rotating the quill; a friction-cup having a hub secured to the quill; clutch devices carried by said friction-cup; a sleeve mounted on the hub; clutch devices carried by said sleeve; gearing also carried by the sleeve; 85 a counter-shaft; gears loosely mounted on said counter-shaft; devices for locking said gears to the counter-shaft; a gear intermediate one of said counter-shaft gears and one of the 90 gears carried by the hub; a fixed gear carried by the counter-shaft; a gear in engagement with said fixed gear and loosely mounted on the driven shaft; and means for connecting said gear to said driven shaft. 95

22. The combination, with a shaft, of a quill loosely mounted on said shaft; a friction-cup having a hub splined to said quill; means for 100 rotating the quill and thereby the friction-cup; a clutch device within the friction-cup, 100 means for actuating said clutch device; a sleeve mounted on the hub; means for reciprocating said sleeve; clutch devices carried by the sleeve and adapted to engage with the clutch devices of the cup; a pair of gears carried by the sleeve; a counter-shaft; a pair of 105 gears loosely mounted on said counter-shaft; clutch mechanisms for locking said loosely-mounted gears to the counter-shaft; a gear intermediate one of the loosely-mounted 110 gears of the counter-shaft and one of the sleeve-gears; a fixed gear carried by the counter-shaft; a gear in engagement with said fixed gear and loosely mounted on the driven shaft; clutch devices carried by said gear; a 115 carrier secured to the driven shaft; clutch devices movable on said carrier and adapted to engage with the clutch devices of the gear; and means for actuating the clutch devices of the carrier. 120

23. The combination, with a shaft, of a quill loosely mounted on said shaft; means for rotating the quill; a hub splined to the quill; a friction-cup carried by the hub; means for connecting said friction-cup to the driven 125 shaft; a sleeve movable on the hub; clutch devices between said sleeve and hub; gears carried by the sleeve; a counter-shaft; gears loosely mounted on the counter-shaft; clutch devices for locking one of said gears to said 130 counter-shaft; clutch devices for locking another of said gears to said counter-shaft; a gear intermediate one of said loosely-mounted gears and one of the gears of the movable

sleeve and in engagement with each of said gears; a pinion fixed to the counter-shaft; a gear loosely mounted on the driven shaft; clutch devices carried by said gear; a carrier; 5 clutch devices mounted on the carrier; and means for actuating said clutch devices to cause them to engage with the clutch devices of the gear.

24. The combination, with a shaft, of a quill 10 loosely mounted on said shaft; means for rotating said quill; a friction-cup having a hub splined to the quill; a carrier secured to the shaft; an expansion-ring secured to said carrier; means for expanding said expansion- 15 ring to lock the friction-cup to the carrier; a sleeve movable on the hub of the friction-cup; a gear carried by said sleeve; means for actuating the sleeve; clutch devices between the gear and friction-cup; a counter- 20 shaft; a gear loosely mounted on said counter-shaft; means for connecting said gear to the counter-shaft; a pinion carried by the counter-shaft; a gear loose on the driven shaft and in engagement with said pinion; 25 clutch devices carried by the gear; clutch devices mounted on the carrier; and means for actuating said clutch devices to cause them to engage with the clutch devices of the gear.

25. The combination, with a driven shaft, of a quill loose on said shaft; a hub splined to said quill; a sleeve movable on said hub; means for clutching the sleeve to the hub; a gear carried by the hub; a counter-shaft; a 30 gear carried by the counter-shaft; means for clutching said gear to the counter-shaft; a gear intermediate the gear on the counter-shaft and the gear of the hub and in engagement with both of said gears; a pinion carried by the counter-shaft; a gear in engagement with said pinion; and means for clutching said gear to the driven shaft.

26. The combination, with a shaft, of a quill loose on said shaft; a hub splined to the quill; 45 a sleeve movable on the hub; means for connecting the hub to the driven shaft; clutch devices intermediate the sleeve and hub; a counter-shaft; a gear loosely mounted on the counter-shaft and in engagement with the 50 gear of the hub; means for reciprocating the sleeve on the hub to cause the clutch devices to engage; means for locking the gear on the counter-shaft to said counter-shaft after said clutch engagement has been made; a pinion 55 on the counter-shaft; a gear loose on the driven shaft; and means for connecting said gear to the driven shaft.

27. The combination, with a driven shaft, of a quill loose on said shaft; means for rotating the quill; means for connecting the quill to the driven shaft, to drive the same at full speed forward; a sleeve; gears carried by the sleeve; means for reciprocating the sleeve; means for connecting the sleeve to the quill; 60 a counter-shaft; a gear loose on the counter-shaft; means for connecting said gear to the counter-shaft; a gear fixed to the counter-

shaft; a gear loose on the driven shaft; clutch-pins carried by said gear; a carrier secured to the driven shaft; clutch-pins movable on the carrier; and means for actuating said clutch-pins to cause them to engage the clutch-pins of the gear and rotate the driven shaft at a slow forward speed.

28. The combination, with a driven shaft, of a quill loose on said shaft; means for rotating the quill; a hub splined to the quill; means for connecting said hub to the driven shaft to rotate the same in one direction; a sleeve movable on the hub; clutch devices between the hub and sleeve; and means for rotating the driven shaft in a reverse direction, said sleeve constituting a part of the reversing means.

29. The combination, with a shaft, of mechanisms for rotating said shaft; means for connecting said mechanisms to the shaft; a cam-shaft; a cam; means for actuating the cam; lever-and-link mechanisms actuated by the cam and controlling the shaft-rotating mechanisms; a device carried by each of the link parts of said lever-and-link mechanisms; and means for keeping said device in fixed relation to the cam.

30. The combination, with a shaft, of means for rotating said shaft at a slow forward speed; means for rotating said shaft at a fast forward speed; means for reversing the rotation of the shaft; a movable sleeve constituting a part of the slow forward and reversing mechanisms; means for connecting said sleeve to the shaft; and a cam having active and non-active portions for actuating said sleeve and said mechanisms.

31. The combination, with a driven shaft, of a quill loose on said shaft; means for rotating the quill; a hub splined to the quill; a friction-cup carried by the hub; means for connecting said friction-cup to the driven shaft; clutch-pins carried by the friction-cup; a sleeve movable on the hub of the friction-cup; gears carried by the sleeve; clutch-pins mounted on one of the gears; means for reciprocating the sleeve; a counter-shaft; a pair of gears loosely mounted on said counter-shaft; clutch devices for locking said gears to the counter-shaft; means for actuating each of said clutch devices; a gear in engagement with one of the gears of the sleeve and with one of the loosely-mounted gears of the counter-shaft; a fixed gear on the counter-shaft; a loose gear on the driven shaft and in engagement with said fixed gear; clutch-pins carried by said loose gear; a carrier splined to the driven shaft; clutch-pins movable in ways of the carrier; means for actuating said clutch-pins to cause them to engage the clutch-pins of said loose gear; a cam; and means intermediate said cam for shifting the clutch-pin-actuating mechanism.

32. The combination, with a shaft, of a quill sleeved on said shaft; a hub rotating with the quill; a clutch element carried by the hub; a clutch element carried by the shaft; means

for actuating one of said clutch elements to connect the shaft and hub; a counter-shaft; and gearing controlled by the hub for changing the speed of the shaft on which the quill is sleeved.

33. The combination, with a shaft, of a quill sleeved on said shaft; a hub carried by and rotating with the quill; a clutch element carried by the hub; a clutch element carried by the shaft; means for actuating the clutch element carried by the shaft to connect the shaft and hub; means for applying power to the quill; a counter-shaft; reversing mechanism of which the hub carried by the quill constitutes a part; and means for connecting said reversing mechanism with the shaft.

34. The combination, with a shaft, of a hub or carrier secured to said shaft; a gear loose on the shaft; clutch devices carried by the gear; clutch devices movable on the hub or carrier; means for actuating said clutch devices of the carrier; and means for rotating the gear and, through the hub or carrier to which it is clutched, the shaft.

35. The combination, with a shaft, of a hub or carrier splined to the shaft; a power-transmitting element loose on the shaft; clutch-pins mounted in guides of the hub or carrier; means for reciprocating said clutch-pins; clutch-pins carried by the power-transmitting element; and means for actuating said element and, through the hub or carrier, the shaft.

36. The combination, with a shaft, of a hub or carrier splined to said shaft, said hub or carrier having open slots; means for rotating the hub or carrier and thereby the shaft at full speed in a forward direction; a gear loosely mounted on the shaft adjacent to said hub or carrier; clutch-pins carried by the gear; means for reciprocating the clutch-pins of the hub or carrier to cause them to engage the clutch-pins of the gear; and means for rotating said gear when such engagement is made, and thereby the hub or carrier, at a slow, forward speed.

37. The combination, with a shaft, of a hub or carrier having longitudinal guideways splined to said shaft; means for rotating the hub or carrier, and thereby the shaft, at a fast speed forward; clutch-pins; means for reciprocating the clutch-pins in the guideways of said hub or carrier; a gear loosely mounted on the shaft adjacent to said hub or carrier; clutch-pins carried by the gear; a counter-shaft; a loose gear carried by said counter-shaft and in mesh with the gear carrying the clutch-pins; means for locking said loose gear to the counter-shaft; and means for rotating the counter-shaft and thereby causing the shaft to which the hub or carrier is splined to rotate at a slow speed in a forward direction.

38. The combination, with a shaft, of a hub or carrier splined to said shaft; a quill loose on the shaft; means for rotating the quill; a hub splined to the quill; means for clutching said hub to the hub or carrier; a gear loose

on the shaft and located adjacent to one end of said hub or carrier; means for clutching the hub or carrier to said gear; means for releasing the clutch devices connecting the hub or carrier and the hub splined to the quill; and means for rotating the gear adjacent to one end of said hub or carrier.

39. The combination, with a driven shaft, of a hub or carrier splined to said shaft; a gear loosely mounted on the shaft adjacent to one end of said hub or carrier; means for clutching the hub or carrier to said gear; a counter-shaft; a gear loosely mounted on said counter-shaft; means for clutching said gear to the counter-shaft; means for rotating said gear when thus locked to the counter-shaft; and a gear carried by the counter-shaft and in mesh with the gear loosely mounted on the driven shaft.

40. The combination, with a driven shaft, of a hub or carrier splined to said shaft and having guideways; clutch-pins mounted in the guideways; a shifting ring mounted upon the hub or carrier and connected with said clutch-pins; means for actuating said shifting ring; a gear loose on the driven shaft and located adjacent to one end of said hub or carrier; clutch-pins carried by said gear and adapted to engage with the complementary pins of the hub or carrier; a counter-shaft; a gear carried by said counter-shaft and in mesh with the gear loose on the driven shaft; and means for rotating said counter-shaft.

41. The combination, with a driven shaft, of a hub or carrier splined to said shaft and having longitudinal guideways; clutch-pins mounted in said guideways; a shifting ring; studs projecting from the shifting ring and in engagement with the clutch-pins; a cam; means controlled by said cam for actuating the shifting ring; a gear loosely mounted on the driven shaft adjacent to one end of the hub or carrier; clutch-pins carried by the gear; a counter-shaft; a gear carried by said counter-shaft and in mesh with the gear loose on the driven shaft; and means for actuating the counter-shaft.

42. The combination, with a driven shaft, of a hub or carrier splined to said shaft and having open slots; clutch-pins mounted in said slots; a shifting ring; studs projecting from said shifting ring passing through the slots of the hub or carrier and engaging said clutch-pins; a revolute cam; means controlled by said cam for actuating the shifting ring; a gear loose on the driven shaft; clutch-pins carried by the gear and adapted to engage the complementary pins of the hub or carrier; a counter-shaft; a gear carried by said counter-shaft, and in engagement with the gear loose on the driven shaft; and means for rotating the counter-shaft.

43. The combination, with a driven shaft, of a hub or carrier splined to said shaft and having longitudinal guideways; a shifting ring mounted on the hub or carrier; clutch-pins mounted in the guideways of said hub

or carrier; studs projecting from the shifting ring and in engagement with said clutch-pins; a revoluble cam; lever-and-link mechanism controlled by said cam for actuating 5 the shifting ring; a power-transmitting element loose on the driven shaft adjacent to one end of the hub or carrier; clutch-pins carried by said power-transmitting element; and means for rotating said power-transmitting element.

44. The combination, with a driven shaft, of a hub or carrier secured to said shaft; an expansion-ring attached to the hub or carrier; a friction-cup; means for actuating said expansion-ring and thereby locking the cup and hub or carrier together; means for rotating the friction-cup; a power-transmitting element located adjacent to said hub or carrier; means for clutching said power-transmitting 15 element to the hub or carrier; and means for rotating the power-transmitting element.

45. The combination, with a driven shaft, of a hub or carrier secured to said shaft; means for driving said hub or carrier and thereby the driven shaft at a fast speed in a forward direction; a power-transmitting element loosely mounted on the driven shaft adjacent to said hub or carrier; means for clutching said power-transmitting element to 25 the hub or carrier; means for rotating said power-transmitting element at a slow speed in a forward direction; and means for reversing the rotation of said power-transmitting element, and, through the hub or carrier 30 clutched thereto, the driven shaft.

46. The combination, with a driven shaft, of a hub or carrier splined to said shaft; an expansion-ring secured to said hub or carrier; a shifting ring mounted on the hub or carrier; means controlled by the shifting ring for actuating said expansion-ring; a friction-cup surrounding said expansion-ring and having a hub; a quill to which the hub of the friction-cup is splined; means for rotating 40 the quill; clutch devices movable on the hub or carrier; means connecting the shifting ring with said clutch devices; a power-transmitting element loose on the driven shaft adjacent to the hub or carrier; clutch devices 45 carried by said power-transmitting element and adapted to engage the clutch devices of the hub or carrier; a counter-shaft; means for rotating said counter-shaft in different directions; and means carried by the counter-shaft for actuating the power-transmitting 55 element loose on the driven shaft.

47. The combination, with a driven shaft, of a hub or carrier secured to said shaft; a friction-cup; means for clutching said friction-cup to the hub or carrier; means for rotating the friction-cup, and thereby the hub or carrier and driven shaft, at full speed in a forward direction; devices for actuating said means; a power-transmitting element loose 60 on the driven shaft adjacent to the hub or carrier; means for clutching said power-trans-

mitting element to the hub or carrier; and means for rotating said power-transmitting element in different directions.

48. The combination, with a shaft, of a hub 70 or carrier secured to said shaft; means for rotating the hub or carrier and thereby the shaft; a cam; means for actuating said cam; a link carrying a pin in engagement with the cam; a rocker movably connected to the link; 75 and devices controlled by the link and connecting the means for rotating the hub or carrier to said hub or carrier.

49. The combination, with a shaft, of a hub 80 or carrier secured to said shaft; means for rotating the hub or carrier; a grooved cam; a link having a pin fitted in the groove of said cam; a rocker to which the link is pivoted; and devices controlled by said link for clutching the means for rotating the hub or carrier 85 to said hub or carrier.

50. The combination, with a shaft, of means for rotating said shaft; a grooved cam; means for actuating the cam; a link having a pin located in the groove of said cam; a rocker connected to said link; and means controlled by 90 the link for actuating the shaft-rotating means.

51. The combination, with a shaft, of means for rotating said shaft; a grooved cam; means 95 for actuating the cam; a link having a pin; a rocker to which one end of the link is pivoted; a yoke having an arm to which the other end of the link is connected; and devices controlled by the yoke for connecting the shaft-rotating means to said shaft.

52. The combination, with a shaft, of mechanisms for rotating said shaft in forward and reverse directions; a cam; means for actuating the cam; links having devices in engagement with the cam; rockers movably connected to the links; and means controlled by said links for connecting the mechanisms for rotating the shaft to said shaft. 105

53. The combination, with a shaft, and with means for rotating said shaft, of a grooved cam having active and non-active portions secured to the shaft; a link having a pin fitted in the groove of said cam; a rocker to which one end of said link is articulated; a movably-mounted yoke having an arm to which the opposite end of said link is pivoted; a driven shaft; a hub or carrier secured to said driven shaft; shaft-rotating mechanism; and means controlled by the yoke for clutching 110 said shaft-rotating mechanism to the hub or carrier. 115

54. The combination, with a driven shaft, of mechanisms for rotating said shaft; a hub or carrier secured to said shaft; a shifting ring mounted on said hub or carrier; means controlled by the shifting ring for clutching one of the shaft-rotating mechanisms to said hub or carrier; means for actuating the shifting ring; a grooved cam; a link pivoted to 125 said shifting ring, and having a pin fitted in the groove of the cam; a rocker to which said 130

link is articulated; and means controlled by the link for throwing another of the shaft-rotating mechanisms into action.

55. The combination, with a driven shaft, 5 of a hub or carrier splined to said shaft; a quill loosely mounted on the shaft; a friction-cup having a hub splined to said quill; means for rotating the quill; means for coupling the friction-cup to the hub or carrier; a sleeve 10 movably mounted on the hub of the friction-cup; means for actuating the sleeve; gears carried by the sleeve; clutch devices between one of the gears and the friction-cup; a counter-shaft; and means controlled by said counter-shaft for actuating the driven shaft in different directions.

56. The combination, with a driven shaft, of a hub or carrier splined to said shaft; a quill loose on the shaft; means for rotating 20 the quill; a device having a hub splined to said quill; means for clutching said device to the hub or carrier; a sleeve mounted on the hub; clutch mechanism carried by the sleeve; supplemental clutch mechanism carried by 25 the friction-cup; means for reciprocating the sleeve; a counter-shaft; and gearing connecting the counter-shaft with the hub or carrier splined to the driven shaft.

57. The combination with a driven shaft, 30 of a hub or carrier splined to said shaft; a friction-cup; clutch-pins carried by said friction-cup; means for coupling said cup to the hub or carrier; means for rotating the friction-cup; a gear having clutch-pins adapted to engage with the clutch-pins of said friction-cup; means for throwing said clutch-pins into engagement with the supplemental clutch-pins; a counter-shaft; gearing carried by the counter-shaft; means for clutching said gearing 40 to the counter-shaft; a gear loose on the driven shaft; a gear carried by the counter-shaft and in engagement with said loose gear; and means for clutching said loose gear to the hub or carrier.

45 58. The combination, with a shaft, of means for rotating said shaft; mechanism for reversing the rotation of said shaft; a cam; means for actuating said cam; a link; a device carried by the link and in engagement with the 50 cam; a rocker to which the link is pivoted; and means connecting said link with a part of the shaft-reversing mechanism.

59. The combination, with a shaft, of means 55 for rotating said shaft; mechanism for reversing the rotation of the shaft; a clutch constituting a part of the shaft-reversing mechanism; clutch-actuating mechanism; a grooved cam; means for actuating said cam; a link having a pin; devices connecting the link 60 with the clutch-actuating mechanism; and a

rocker for controlling the movement of the link upon its pin.

60. The combination, with a shaft, and with means for actuating the same, of a grooved cam having active and non-active portions 65 secured to said shaft; a link; a pin carried by the link, said pin entering the cam-groove; a rocker to which the link is pivoted; and a shiftable element to which said link is connected. 70

61. The combination, with a grooved cam, of means for actuating said cam; a link; a pin carried by the link and entering the groove of the cam; a rocker connected to the link; and a shiftable element also connected to the 75 link.

62. Speed controlling and reversing mechanism comprising the following instrumentalities in combination: a shaft; means for rotating the shaft at full speed forward; 80 means for rotating said shaft at slow speed forward; means for reversing the rotation of said shaft; a cam having a series of active and passive portions; a link and connections operated by the cam for throwing the full-speed shaft-actuating mechanism into and out of action; devices actuated by said link for throwing the slow-speed, shaft-actuating mechanism into and out of action; a second 85 link; and devices operated by said second link for throwing the shaft-reversing mechanism into and out of action.

63. Speed controlling and reversing mechanism comprising the following instrumentalities in combination: a shaft; means for 90 rotating said shaft at slow speed in a forward direction; means for rotating said shaft at fast speed in a forward direction; means for reversing the rotation of said shaft; a grooved cam having a series of active and passive 95 portions; a link carrying a pin entering the cam-groove; connections from the link for throwing the mechanism for actuating the shaft at a slow speed forward into and out of action; connections from the link for throwing the mechanism for actuating the shaft at 100 fast speed in a forward direction into and out of action; a rocker pivoted to the link; a second link having a pin entering the cam-groove; a rocker articulated to said second link 105 for throwing the shaft-reversing mechanism into and out of action.

In testimony whereof I affix my signature in presence of two witnesses.

MOSES C. JOHNSON.
